FIG. 4

○ 适用范围

消防、水暖、地暖、太阳能、空气能、蒸汽、油管、PPR、仪表等各种尺寸管径的外丝接。（不适用于气体输送）

○ 产品使用说明

三圈牌密封带表面有高分子涂层，适用于各种尺寸管径的密封，开袋即用，未用完浸水可再次使用，不影响产品密封效果。操作简单，直接缠绕3~5圈即可（需根据实际公差确定缠绕圈数）。可承压输送水介质强度≤6.0Mpa (60kg/cm²)。

耐温环境：-50°C~330°C

○ 企业标准

产品符合企业Q/ZCX 002-2020标准；经检验符合国家饮用水标准《GB 5749-2006生活饮用水卫生标准》；持有国家化学建筑材料测试中心测试承压≥40Kg/cm²的承压报告；产品通过欧盟RoHS认证。

○ 规格 15mmx10m/袋

○ 毛重 45kg/100袋
